UNITED STATES PATENT OFFICE.

GEORGE B. WILKINSON, OF CLARKSBURG, WEST VIRGINIA.

SWITCH THROWER.

Application filed September 1, 1925. Serial No. 53,910.

This invention relates to an apparatus by means of which a switch point may be adjusted in order to control the movement of a car and cause it to either proceed along the 5 main track or pass onto a track branching from the main track.

One object of the invention is to so construct the apparatus that adjustment of the switch may be controlled by the motorman 10 of a car without it being necessary to alight from the car. When it is necessary for the motorman or conductor to alight from the car and adjust the switch to the desired position and then return to the car, loss of time 15 is involved and in addition it is necessary for the motorman to leave the car without a person of proper authority in control of it.

Another object of the invention is to so construct the track carried mechanism of the 20 switch control apparatus that it may be enclosed in a housing where it will be protected from exposure to the weather and prevented from being clogged by snow, ice or dirt.

25 Another object of the invention is to so form the housing that an open-ended trough may extend through the housing to receive plungers forming part of the car carried actuating mechanism and have the trough divided into separate passages to receive the 30 plungers so that when one plunger is moved to an operative position there will be no danger of the switch point being improperly set.

35 Another object of the invention is to so mount the plungers of the car carried actuating mechanism that they may be releasably held in a depressed operative position and automatically returned to the elevated 40 or inoperative position after the switch point has been adjusted.

Another object of the invention is to so form and mount the latches for the plungers that they may be moved to an operative position by the plungers when the plungers are moved to an operative position and moved to release the plungers through engagement with abutments in the trough after the switch point has been set.

50 This invention is illustrated in the accompanying drawings, wherein

Figure 1 is a view showing a portion of a track in top plan and the track carried mechanism in longitudinal section on the line 1—1 of Fig. 2;

Fig. 2 is a vertical sectional view through

the track carried mechanism with the platform or floor of the car shown in section and the car carried mechanism in front elevation, and

60

Fig. 3 is a sectional view taken on the line 3—3 of Fig. 2.

The apparatus forming the subject-matter of this invention permits the switch point 1 to be swung transversely of the frog 2 so 65 that a car moving along the rails 3 of the main line of trackage may be permitted to continue along the main line or be guided onto the rails 4 constituting a branch line or side track. The rails are, of course, 70 mounted upon the usual ties 5 and are of a conventional construction.

The track carried mechanism is contained in a housing 6 formed of metal or any other suitable material and at its sides provided with ears 7 through which spikes or other fasteners 8 may be passed to firmly secure the housing upon certain of the ties 5. When in place, the housing extends longitudinally of the main track and adjacent the 75 free end portion of the switch point. A trough 9 extends longitudinally through the housing and is open at its ends, a partition 10 being disposed longitudinally in the trough and dividing the trough into side 80 compartments 11 and 12. Cover plates 13 are provided for the housing at opposite sides of the trough 9 and releasably held in place by fasteners 14 which preferably consist of bolts so that the cover plates may 85 be easily removed when necessary. It should be noted that the trough extends through the upper portion of the housing with its bottom spaced from the bottom of the housing, as shown in Fig. 2. A hollow side arm 15 90 extends transversely from the forward end portion of the housing and of such length that, when the housing is secured to the ties as shown in Fig. 1, the outer end portion of the arm 15 may extend into an opening 16 95 formed in the frog 2 of the track.

The drawbar or link 17 which is secured at one end in an opening formed transversely through the switch point extends longitudinally through the side arm 15 of the 100 housing with its inner end portion extending into the housing and pivotally connected with the forward end of a rocker bar 18 which is disposed longitudinally of the housing and pivotally mounted upon a post 19 projecting upwardly from the bottom of the housing beneath the trough. At its for- 105 110

ward end the rocker bar is pivotally connected with a cross bar 20 consisting of a main section and a short auxiliary section 21 pivoted to the main section. Levers 22 and 23 extend longitudinally of the housing at opposite sides of the trough and are pivotally mounted upon posts 24 arising from the floor of the housing and each lever has its rear end portion bent downwardly, as shown in Fig. 2, and pivotally connected with the cross bar, the lever 22 being connected with the outer end of the auxiliary cross bar section and the lever 23 being connected with the outer end of the main section of the cross bar. At their forward ends the levers are formed with side arms 22' and 23' which are adapted to alternately move through the openings 25 formed in the side walls of the trough and extend transversely across the passages 11 and 12 for engagement by plungers forming part of the car carried actuating means.

The car carried actuating mechanism includes a bracket formed, as shown in Fig. 3, and including a head board 26 and a depending forwardly inclined arm 27, the head board being secured to the under face of the car platform or floor 28 by bolts or other suitable fasteners 29 and the depending arm 30 being strengthened by a brace 30 disposed at an incline between the ends of the arm. Sleeves 31 are provided at the lower forward end of the arm 27 and braced by webs 32 and serve a slidably mount plungers 33 and 34. These plungers are provided with upwardly extending rods 33' and 34' of a length to extend through the floor or platform of the car and at their upper ends terminate in heads upon which the motorman is to place his foot when forcing the plungers downwardly against the action of the springs 35 coiled about the rods and serving to yieldably retain the plungers in an elevated and inoperative position. At its lower end each plunger is formed with a notch or recess 36 adjacent the upper end of its curved and forwardly inclined lower end. The plungers have their lower ends curved, as shown in Fig. 3, so that when moved downwardly they may easily force the elongated latches 37 downwardly to a depending position against the action of the springs 38 coiled about the pin 39 upon which the latches are pivotally mounted and normally retaining them in an elevated inoperative position, as shown at the right in Fig. 2. A tooth 40 extends from each of the latches and is adapted to enter the notch 36 of its cooperating plunger, as shown in Fig. 3, so that when the plunger is forced downwardly to the operative position it will be firmly held against return to the inoperative or elevated position without it being necessary for the motorman to keep his foot upon the head of the plunger. It should be further noted that the latch is of

such length that when the plunger is moved downwardly and secured by the latch the lower end portion of the latch extends below the lower end of the plunger to such an extent that it may engage with the abutment 41 in the bottom of the trough compartment through which it moves.

When the improved switch point adjusting apparatus is in use, the housing 6 is secured upon the ties with the outer end portion of the arm 15 fitted in the opening 16 formed in the frog 2 and the outer end portion of the link secured in an opening drilled or otherwise formed in the switch point. When the switch point is positioned to direct a car along the main track, the rocker bar is disposed as shown in Fig. 1 with the side arm of the lever 23 projecting into the compartment 12 of the trough. When a car approaches the intersection of the side track with the main line and it is desired to have the car moved from the main line onto the side track, the motorman presses downwardly upon the head of the plunger 34 and forces this plunger downwardly to the position shown in Figs. 2 and 3 in which position it will be securely held by its cooperating latch. The car is then advanced and as the depressed plunger passes through the compartment 12, its lower end portion engages the side arm of the lever 23 and swings the side arm forwardly. Since the lever is pivoted intermediate its length, it will, of course, turn and its arm move outwardly through the slot in the side wall of the trough. At the same time a pushing action will be exerted upon the cross bar 20 and the rocker bar swung upon its pivot 19 to push upon the link or drawbar 17 and force the switch point to a position to engage the wheels of the car and direct the car onto the side track. At the same time the lever 22 will be swung to project its side arm into the compartment 11 of the trough so that if a following car is to proceed along the main track the side arm of the lever 22 may be engaged by the plunger 33 which will be depressed and restore the switch point to the position shown in Fig. 1. After the depressed plunger has moved the cooperating lever to adjust the switch point, the lower end of the latch engages the abutment 41 in the trough compartment through which it moves and is thereby swung rearwardly to such an extent that its tooth 40 moves out of the notch 36 in the plunger and releases the plunger so that its spring 35 will return it to the elevated position. As soon as the latch passes over the abutment, its spring 38 swings it upwardly to the inoperative position in which position it extends horizontally and forwardly across the lower end of the sleeve for engagement by its cooperating plunger when the plunger is again forced downwardly. Of course, if the switch point is al-

ready set in the proper position to permit the car to travel in the proper direction, it is not necessary for the motorman to operate the switch point adjusting apparatus but if the switch point is not well lighted the motorman in order to be sure of going in the proper direction may press the proper plunger downwardly. In case the switch point is already set no adjustment will take place and as soon as the depressed latch engages its cooperating abutment 41 it will be moved to the releasing position and its plunger allowed to return to the inoperative position. Any water which may collect in the housing will drain out through the openings 42 formed in its bottom.

Having thus described the invention, I claim:

1. A switch thrower comprising track carried mechanism adapted for connection with a movable switch point and including an operating lever, car carried actuating means including an element movable to an operative position for engaging said lever

25 as a car passes over the track carried mechanism, a latch adapted to releasably hold said element in an operative position, and means associated with the track mechanism to automatically move said latch to an inoperative position after said element has passed out of engagement with said lever.

30 2. A switch thrower comprising track carried mechanism adapted for connection with a movable switch point and including an operating lever, a housing for said mechanism, said lever being adapted to project out of said housing, car carried actuating means including an element movable to an operative position for engaging said lever as a car passes over the track carried mechanism, a latch adapted to releasably hold said element in an operative position, and an abutment carried by said housing to engage said latch and move the latch to a releasing position to permit return of said lever engaging element to an inoperative position after passing out of engagement with the lever.

35 3. A switch throwing mechanism comprising a housing adapted to be mounted between the rails of a track, an open-ended trough extending longitudinally through said housing and opening through the upper wall thereof, mechanism in said housing including a link projecting outwardly from the housing and adapted for connection with a switch point of a track and operating levers adapted to be alternately projected into the trough through opposite side walls thereof for engagement by car carried actuating means releasably held in an operative position to move longitudinally through the trough, and an abutment in said trough to cause return of the actuating means to an inoperative position after en-

gaging the lever projecting into the trough and moving the lever to throw the switch point.

4. A switch throwing mechanism comprising a housing adapted to be mounted between the rails of a track, an open-ended trough extending longitudinally through said housing and opening through the upper wall thereof, mechanism in said housing including a link projecting outwardly from the housing and adapted for connection with a switch point of a track and operating levers adapted to be alternately projected into the trough through opposite side walls thereof for engagement by car carried actuating means releasably held in an operative position to move longitudinally through the trough, a partition extending longitudinally in said trough, and abutments in the bottom of said trough upon opposite sides of said partition to cause return of the actuating means to an inoperative position after operative engagement with the lever extending into the trough.

5. A switch throwing mechanism comprising a housing adapted to be mounted between the rails of a track adjacent a movable switch point, an open-ended trough extending longitudinally through said housing, a rocker bar extending longitudinally in said housing and having movement transversely of said trough, switch point engaging means connected with one end of said rocker bar and extending out of said housing, levers pivotally mounted in said housing at opposite sides of said trough and connected with the other end of said rocker bar and moving in opposite directions when one is moved, said levers being provided with side arms adapted to alternately pass into said trough through openings in the sides thereof into position for engagement by car carried actuating means moved longitudinally through the trough.

6. A switch throwing mechanism comprising a housing adapted to be mounted between the rails of a track adjacent a movable switch point, an open-ended trough extending longitudinally through said housing and opening through the upper wall of the housing, a rocker bar extending longitudinally in said housing and pivotally mounted for swinging transversely beneath the trough, said trough having opposed openings in its side walls, levers pivotally mounted in said housing at opposite sides of said trough and at one end formed with side arms adapted to pass into the trough through the openings in the side walls thereof, the other end portions of said levers being extended downwardly and terminating below said trough, a cross bar joining the downturned ends of said levers and extending transversely beneath said trough

pivottally connected with one end of said rocker bar, and a link connected with the other end of said rocker bar and extending out of said housing for connection with the 5 switch point.

7. A switch throwing mechanism comprising a housing adapted to be mounted between the rails of a track adjacent a movable switch point, a trough extending longitudinally through said housing and open at its 10 ends, a rocker bar extending longitudinally in said housing beneath said trough and pivottally mounted intermediate its ends, a link pivoted to one end of said rocker bar and projecting from one side of said housing and adapted to be connected with the switch 15 point, a cross bar extending transversely beneath said trough and intermediate its length pivoted to the other end of said rocker bar, and levers pivottally mounted in said housing at opposite sides of said trough and pivottally connected 20 to their ends to the ends of said cross bar, said levers having their other end portions formed with side arms adapted to alternately extend into said trough through the sides thereof, and actuating means adapted to be carried by a car and disposed to pass through said trough as the car moves along the track and impart movement to said rocker bar by engagement with one of said levers.

15. A switch throwing mechanism comprising a housing adapted to be mounted between the rails of a track adjacent a movable switch point, a cross bar extending transversely beneath said trough and intermediate its length pivoted to the other end of said cross bar, the other end portion of said levers being formed with side arms adapted to alternately project into said trough through opposite sides thereof for engagement by car carried actuating means moved through said trough.

30. 8. A switch throwing mechanism comprising a housing adapted to be mounted between the rails of a track adjacent a movable switch point, a trough extending longitudinally through said housing and open at its ends, a rocker bar extending longitudinally in said housing and pivottally mounted intermediate its length for swinging transversely of the trough, a link pivoted to one end of said rocker bar and projecting transversely from said trough and adapted for engagement with the switch point, a cross bar pivoted intermediate its ends to the other end of said rocker bar, and operating means connected with opposite ends of said cross bar and movably mounted in said housing and adapted to alternately project into said trough for engagement by car carried actuating means moved through said trough.

115. 9. A switch throwing mechanism comprising a housing adapted to be mounted between the rails of a track adjacent a movable switch point and including a hollow side arm open at its outer end and at its inner end communicating with the housing, 120 a trough extending longitudinally through said housing and open at its ends, a rocker bar extending longitudinally in said housing and pivottally mounted intermediate its ends for swinging transversely of the housing, a link extending longitudinally through said arm with one end pivottally connected with one end of said rocker bar and its other end projecting from the outer end of the arm and adapted for connection with the 125 switch point to impart transverse movement

thereto when said rocker bar is moved, a cross bar pivoted intermediate its length to the other end of said rocker bar, levers pivottally mounted in said housing at opposite sides of said trough and pivottally connected 70 to their ends to the ends of said cross bar, said levers having their other end portions formed with side arms adapted to alternately extend into said trough through the sides thereof, and actuating means adapted to be carried by a car and disposed to pass through said trough as the car moves along the track and impart movement to said rocker bar by engagement with one of said levers.

10. In a car carried actuating mechanism for a switch throwing mechanism, a frame adapted to be secured in depending relation to a car floor, a vertical bearing carried by said frame between the sides thereof, a plunger slidable in said bearing and provided with an upwardly extending rod of a length to project through the floor of the car, means yieldably retaining said plunger in a raised inoperative position, and a latch adapted to releasably retain said plunger in a lowered operative position for engagement with an operating element of a track carried switch point setting mechanism, said latch adapted to be moved to a releasing position through engagement with an abutment.

11. In a car carried actuating mechanism for a switch throwing mechanism, a frame adapted to be secured in depending relation to a car floor, a vertical bearing carried by said frame between the sides thereof, a plunger slidable in said bearing and provided with an upwardly extending rod of a length to project through the floor of the car, means yieldably retaining said plunger in a raised inoperative position, and a latch pivoted adjacent the lower end of said sleeve and yieldably held in a raised position to extend across the lower end of the sleeve, said plunger when moved downwardly engaging the latch and swinging the same downwardly and interlocking therewith to releasably retain the plunger in a set position, the latch when swung downwardly extending from the plunger and adapted to be moved to a plunger releasing position through engagement with an abutment.

115. 12. In a car carried actuating mechanism for a track carried switch throwing mechanism, a frame including a head plate adapted to be secured beneath a car floor, an arm extending downwardly from said head plate at a forward incline, a vertical sleeve carried by the lower end of said arm, a plunger slidable in said sleeve and having a latch receiving recess adjacent its lower end, a push rod extending upwardly from said sleeve through said head plate and of a length to extend upwardly through the car floor, a spring coiled about said rod and

normally holding the plunger and rod elevated, a latch pivoted at the rear side of the lower end of said sleeve, and a spring engaging said latch and normally holding the latch swung upwardly and forwardly across the lower end of said sleeve, said plunger when moved downwardly forcing said latch downwardly into a depending position for locking engagement in the recess of the

plunger to hold the plunger in a set position and said latch when forced downwardly extending below the plunger and adapted to be moved to a releasing position through engagement of its lower end with an abutment upon a track.

In testimony whereof I affix my signature.

GEORGE B. WILKINSON. [L. S.]
